UNITED STATES PATENT OFFICE.

JOHN FAULDS, OF OAK PARK, ILLINOIS, ASSIGNOR OF ONE-HALF TO JOHN I. MARSHALL, OF CHICAGO, ILLINOIS.

BAKE-OVEN.

1,148,669.

Specification of Letters Patent.

Patented Aug. 3, 1915.

Application filed January 4, 1915. Serial No. 468.

To all whom it may concern:

Be it known that I, JOHN FAULDS, a citizen of the United States, and a resident of Oak Park, county of Cook, and State of Illinois, have invented certain new and useful Improvements in Bake-Ovens, of which the following is a specification, and which are illustrated in the accompanying drawings, forming a part thereof.

10 The invention relates to bake ovens and more particularly to those of the type known as continuous ovens wherein the baking compartment is closed and the gases from the fire are confined within flues.

15 The invention contemplates improvements in bake ovens of this type whereby the ovens may be quickly erected at the place of use by merely fitting together the previously constructed parts and the heating of the 20 baking compartment is rendered more efficient and more readily controlled.

The invention further contemplates that in some instances a plurality of baking compartments may be employed, in which case 25 improvements are provided for controlling the heating of all of the compartments.

The object of the invention is to provide bakers' ovens of improved construction and more efficient operation.

30 In the accompanying drawings, Figure 1 is a perspective view showing an oven embodying the features of improvement provided by the invention some of the parts being broken away to show details of the supporting frame work and internal construction, Fig. 2 is a central transverse sectional view of the oven, the planes of the section being indicated by the broken line 2-2, on Fig. 1, Fig. 3 is a central longitudinal sectional view, Figs. 4 and 5, are detail perspective views showing the arrangement of the floor beams of the frame work and the flues which connect with the furnace in two different positions of the latter.

45 The oven provided by the invention comprises a supporting frame work generally designated 10. This frame work is shown as made principally from a plurality of metal angle bars, including the floor beams 11, 12, 50 uprights 13, 14, and the roofing members 15, 16.

The floor beams 11 and 12 are preferably

arranged in two rectangular frames, each of the beams 12 being parallel with one of the beams 11 but within the space inclosed by 55 said beams 11. The beams 11 and 12 accordingly serve as the lower edges of a set of double walls including the inner and outer side walls 17, 18 and the inner and outer end walls 19, 20. The uprights 13, 14 are desirably arranged in two sets. As shown the uprights 13 are connected with the floor beams 11 and serve as corner posts for the outer side and end walls 18 and 20. Similarly, the uprights 14 rise from the floor 60 beams 12 and enter into the construction of the inner side and end walls 17, 19. If desired, a strengthening band extending entirely about the oven may be provided by the use of a set of horizontal beams 21, each connecting two adjacent corner posts 13 at 65 about their mid height.

The inner and outer side and end walls 17, 18, 19, 20 are preferably completed by the use of sheet metal panels 22, 23. The 75 panels 22 extend horizontally between the corner posts 13 of the outer walls 18, 20, above and below the beams 21. The panels 23 extend vertically between the upper and lower edges of the inner walls 17, 19, between the uprights 14.

The roofing members 15, 16, connect the higher ends of the uprights 13, 14, respectively and are spaced apart to provide frames for outer and inner covers 24, 25. 85 The outer cover 24 is shown as being of sheet metal. The inner cover 25 is preferably of tile. To provide an economical use of the heat for baking and in order that the oven may present a cool exterior, the space 90 between the inner and outer walls 17, 19, and 18, 20, and between the outer and inner covers 24, 25, is preferably filled with a loose heat insulating material 26.

The drawings show upper and lower baking compartments 27 and 28. Each baking compartment has a chambered hearth, as 29, and roof, as 30, the horizontally disposed chambered wall 31 extending between the upper compartment 27 and lower compartment 100 28, constituting the hearth of the former and the roof of the latter. Charging doors 32, 33, each mounted in a frame 34 which is fitted into and extends between the

inner and outer walls 19, 20 at one end, provide access to the chambers of the baking compartments 27, 28, in the usual way. The two walls, as 35, of each of the hearths 29 and 5 31, and the lower wall 36, of the chambered roof 30 are each constructed of tile and each is supported in a frame work of angle bars, as 37, (Figs. 1 and 3) which are carried by the uprights 14, of the inner side and end 10 walls 17, 19. The inner cover 25 of the oven structure constitutes the upper wall of the chambered roof 30 of the baking compartment 27.

The furnace is generally designated 38. 15 It is located below the hearth 29 of the lower baking compartment 28, and may be placed adjacent either end of the oven, in order that the oven may be fired from either end. For this purpose a frame, 39, 40, for receiving 20 a door panel 41 is fitted in the walls 19, 20, at each end. When the furnace 38 is placed near the front oven, as in Figs. 1, 2, 3 and 4, the door panel 41 is fitted in the frame 39 and a closed panel 42 (Fig. 3) is 25 fitted in the frame 40. In event the oven is to be fired from the back, the furnace 38 is placed, as in Fig. 5, and the door panel 41 is fitted in the frame 40. In this instance the closed panel 42 is fitted in the frame 39. 30 A flue 43 preferably extends transversely beneath the hearth 29 at the mid length of the oven structure. This flue is shown as comprising an intermediate T-section 44 which has swiveled connection with each 35 of the outer sections, as 45, 46. This arrangement provides that the intermediate T-section 44, may be reversed for connection of its central leg 47 with the furnace 38, in either position of the latter. The two outer 40 sections 45, 46, of the flue 43 are turned forwardly at their outer ends and each connects with a flue box 48 which is located at the corresponding side of the furnace near the front end of the oven. Each flue box 48 is 45 supported in an elevated position beneath the hearth 28, as upon legs 49.

A vertical flue 50, extends upwardly from each of the flue boxes 48 between the inner and outer side walls 17, 18, of the oven. As 50 shown, each of the flues 50, takes the form of a sheet metal box which is fitted against the outside face of the adjacent sheet metal panel 23 of the corresponding inner side wall 17. The two ends of the flues 50 are 55 inturned, as 51, 52 (Fig. 2) and extend through the panel 23 for entering the flue box 48 and the chamber of the roof 30 of the baking compartment 27, respectively. Each flue 50, preferably also has an intermediate 60 opening 53, in line with the chamber of the hearth 31. Each of these openings is surrounded by a flange 54 which also extends through the adjacent side wall panel 23 and enters the said hearth chamber.

65 To permit the heating of the two baking

compartments 27, 28, to be effectively regulated, provision is preferably made for causing the furnace gases to pass either through the chamber of the hearth 31, or directly to the chamber of the roof 30. This is conveniently accomplished by providing dampers 70 55 (only one of which is shown) for controlling the opening 53. Each of these dampers takes the form of a plate which is hingedly connected with the wall of the corresponding flue 50 upon the inside along the upper edge of the opening 53, as at 56 (Fig. 2), the arrangement being such that the damper 55 covers the opening 53 in one position and extends across the chamber of the flue 50, 80 above the opening 53, in the other position. Each damper 55, may be provided with a crank 57 for operating the same. As it is desirable to operate the two dampers simultaneously, a single operating rod 58 is 85 preferably employed. As shown, this rod extends continuously across the top of the oven in a conveniently accessible position near the front of the same and the two ends of the rods are turned downwardly and enter the chamber of the flues 50, for connection with the cranks 57 (Fig. 2).

To prevent the hearth 29 being over heated by radiation from the furnace 39, provision is preferably made for permitting a 95 circulation of cool air through the chamber of this hearth. As shown, the door panel 41 is provided with openings 59, which communicate with the chamber of the hearth 29 and are controlled by a damper 60.

In order that the gases which enter the chamber of the hearth 31 and the air which enters the chamber of the hearth 29 may be conveyed to the chamber of the roof 30, the chambers of both of these hearths are connected with the chamber of the roof 30 at the rear end of the oven, as by flues 61, 62 and 63. Each of the flues 61, 62 and 63, preferably takes the form of a sheet metal box which is fitted against the outer face of one of the sheet metal panels 23, of the adjacent inner end wall 19, and has its opposite ends inturned, as at 64, and 65, (Fig. 3) for extending through the said sheet metal panel and entering the corresponding chamber. As shown, the flue 61 serves for connecting the chamber of the hearth 31 with the chamber of the roof 30 and is located at the mid width of the oven. The flues 62 and 63 both serve for connecting the chamber of the hearth 29 with the chamber of the roof 30. These flues are preferably located upon opposite sides of the flue 61, as most clearly appears in Figs. 1 and 2.

The gases and air which are delivered to the chamber of the roof 30 are carried away by a smoke pipe 66. As shown, this smoke pipe connects with a flue box 67 which is fitted between the covers 24, 30, adjacent the front end of the oven and is open at the bot-

tom for communication with the chamber of the roof 30. The flue box 67 is conveniently supported by being mounted upon a pair of laterally separated channels 68, 69, (Fig. 1). These channels extend longitudinally through the chamber of the roof 30 for a portion of its length. When the furnace gases enter the chamber of the roof 30 directly from the flues 50, the channels 68, 69 serve for diverting them toward the near end of the oven before entering the flue box 67. If desired, a sliding damper 70 may be provided for controlling the smoke pipe 66.

The arrangement provides that the oven 15 may be easily erected at the place of use from previously constructed parts; that the firing may be from either end without change in the construction of such parts, and the temperature of both baking compartments 20 may be effectively regulated.

I claim as my invention,—

1. In a bake oven, in combination, a baking compartment having a chambered hearth, a furnace, a flue and a damper arranged to divert the furnace gases from the flue into the chamber of the said hearth when in one position and to separate the flue from the said hearth chamber in a different position.

2. In a bake oven, in combination, a baking compartment having a chambered hearth and roof, a furnace, a flue leading from the furnace to the said roof chamber and having a port opening communicating with the hearth chamber, a flue connecting the hearth and roof chambers and a damper controlling the said port opening and arranged in its open position to intercept the travel of gases through the first mentioned flue beyond the port opening.

3. In a bake oven, in combination, a baking compartment of rectangular shape having a chambered hearth and roof, a furnace below the hearth, a pair of flues extending from the furnace to the roof chamber at opposite sides of the baking compartment near one end of the same and each having a port opening communicating with the hearth chamber, a flue connecting the hearth and roof chambers at the other end of the compartment and dampers controlling the said port openings, each damper being arranged in its open position to intercept the travel of gases through the corresponding flue beyond its said port opening.

4. In a bake oven, in combination, a baking compartment of rectangular shape, a flue extending transversely below the baking compartment at its mid length, said flue including a reversible fitting having a port opening which faces in the directions of the opposite ends of the baking compartment in the two positions of the fitting and a furnace constructed to be interchangeably located below the two ends of the baking com-

partment for connection with the said port opening in the corresponding position of the fitting.

5. In a bake oven, in combination, a pair of superimposed baking compartments each having a chambered hearth, the hearth of the upper compartment constituting the roof of the lower compartment and the upper compartment also having a chambered roof, a furnace below the hearth of the lower compartment, air ports opening into the chamber of the hearth of the lower compartment, a damper controlling the said air ports, a flue leading from the furnace to the chamber of the roof of the upper compartment and having a port opening communicating with the chamber of the hearth of the upper compartment, flues connecting the chamber of the two hearths with the chamber of the roof of the upper compartment, and a damper controlling the said port opening of the first mentioned flue and arranged in its open position to intercept the travel of gases through said flue beyond its said port opening.

6. A bake oven comprising, in combination a pair of superimposed rectangular baking compartments, a furnace located centrally below the hearth of the lower compartment, a pair of parallel horizontal flues, one extending lengthwise between the roof of the lower compartment and the hearth of the upper compartment and the other extending through the roof of the upper compartment, a second pair of flues extending laterally in opposite directions from the furnace to one end of the lower baking compartment adjacent opposite sides of the same and thence upwardly to the roof of the upper compartment with openings into each of the flues of the first mentioned pair, a damper in each of the flues of the second mentioned pair between the openings of the corresponding flue into the two flues of the first mentioned pair, and connection between the two flues of the first mentioned pair at that end of the oven which is remote from the upwardly extended portions of the flues of the second mentioned pair.

7. A bake oven comprising, in combination, a pair of superimposed rectangular baking compartments, a furnace located centrally below the hearth of the lower baking compartment adjacent one end of the same, a pair of parallel horizontal flues, one extending lengthwise between the roof of the lower baking compartment and the hearth of the upper baking compartment and the other extending through the roof of the upper baking compartment, a second pair of flues extending laterally in opposite directions from the inner end of the furnace to the two sides of the oven thence forwardly to the front end of the oven and upwardly to the roof of the upper baking com-

partment with openings into each of the flues of the first mentioned pair, a damper in each of the flues of the second mentioned pair between the openings of the corresponding flue into the two flues of the first mentioned pair and connection between the

two flues of the first mentioned pair at the rear end of the oven.

JOHN FAULDS.
